UNITED STATES PATENT OFFICE

WALTER MYERS, OF BRIDGEPORT, CONNECTICUT, ASSIGNOR TO THE SINGER MANUFACTURING COMPANY, OF ELIZABETH, NEW JERSEY, A CORPORATION OF NEW JERSEY

EMBROIDERING MACHINE

Application filed January 26, 1928. Serial No. 249,506.

This invention relates to improvements in sewing machines for embroidering and more especially to embroidering machines of the type having a universal work-feeding mechanism directionally controllable manually during the operation of the machine as exemplified, for instance, by the disclosure, in my prior Patent No. 1,325,033, Dec. 16, 1919.

The present invention has for its primary object to adapt universal-feed embroidering machines for conveniently sewing or embroidering any portion of work of large sizes, such as carpets or rugs.

More specifically, this invention has for an object to improve the feeding mechanism of universal-feed embroidering machines, whereby a selected stitch-length will be uniform throughout a seam regardless of changes in the direction of the seam. A further object of the invention is to provide improved feed-direction and stop-motion controlling means. A still further object of the invention is to provide a universal-feed embroidering machine free of projecting parts below the machine bed, whereby the machine may be more conveniently handled and transported.

To the attainment of the objects of the invention, the machine is constructed with a cloth-plate and overhanging bracket-arm sufficiently long to conveniently accommodate wide work, such as rugs, etc. The reciprocatory looper-operating shaft, usually employed in the chain-stitch type of universal-feed embroidering machines, is actuated by means of a bell-crank lever, which in the present instance is fulcrumed above the cloth-plate of the machine and preferably within the bracket-arm standard, whereby said lever is disposed entirely within the machine-frame outline.

A hand-crank is provided upon a short, vertical shaft journaled in the machine bracket-arm adjacent its head, which hand-crank controlled shaft is directly geared to the feed-direction controlling shaft journaled in said bracket-arm, in order to manually control the direction of feed. To also manually control the operation of the machine, the hand-crank is operable to control a stop-motion device through connecting mechanism housed with-

in the machine bracket-arm, means being provided for conveniently locking a part of said mechanism in position to permit continuous operation of the machine without requiring the usual control by the hand-crank.

For the purpose of obtaining a selected, uniform length for the stitches of a seam, regardless of the seam direction, the usual feed-lever actuating cam is made angularly adjustable about a center coinciding substantially with the point of engagement of the feed-lever with its actuating cam at the beginning of the feed-actuating movement of said cam. By means of this construction, the feeding-foot occupies a constant position with respect to the needle at the beginning of the feeding movement and will therefore have a uniform extent of work-feeding movement, in accordance with the adjusted position of the actuating cam, and this regardless of the direction of feed. The work-plate of the machine surrounding the needle-aperture therein is dished and has a center of curvature corresponding to the point of intersection of the transverse pivotal axes of the feeding-foot carrying bar, whereby the feeding-foot uniformly engages the work throughout feeding movements in any direction and has no tendency to either distort or pull the work by reason of the pivotal axes of the feed-bar.

In the accompanying drawings, Fig. 1 is a front side view in elevation and partly in section of a machine containing the present improvements, the bracket-arm cover-plate being removed. Fig. 2 is a front end elevation of the machine bracket-arm head and bed-plate, the feeding-foot being partly broken away. Fig. 3 is a detail view of the device employed for yieldingly holding the needle-actuating shaft of the machine in inoperative position. Fig. 4 comprises perspective views of the feed-finger actuating cam and its support.

Referring to the drawings, the sewing machine is constructed with a cloth or bed-plate 1, from which rises the vertical standard 2 of the overhanging bracket-arm 3, terminating in the head 4 to which is suitably secured the supporting frame 5.

Journaled in a suitable bearing provided

100

in the standard 2 is a short actuating shaft 6 carrying at its outer end the combined balance-wheel and belt-pulley 7. The shaft 6 is counter-bored at its inner end to provide a bearing for the reduced end 8 of the needle-and-feed-actuating shaft 9, the opposite end of the shaft 9 being journaled in a suitable bearing in the bracket-arm 3.

Supported for rotation about a vertical axis, in bearings provided in the supporting frame 5, is a cylinder 10 within the upper end of which is splined a short, hollow needle-bar 11 partaking of any rotations of the cylinder and capable of vertical reciprocations with respect to said cylinder. Secured within the needle-bar by a set-screw 12 is a hook-needle 13, the needle-bar 11 being operatively connected with a driver 14; vertically reciprocated in the usual manner from the shaft 9.

Cooperating with the needle 13 below the cloth-plate, in the formation of either chain- or drop-stitches, is a vertical axis looper 15 upon the upper end of a shaft suitably journaled upon the machine-frame and having a spiral-gear 16 in mesh with a spiral driving-gear 17 upon the forward end of a rotary and endwise-reciprocatory shaft 18. The spiral-gear 17 is adjustably secured upon the shaft 18 so that it may be shifted upon said shaft to partially rotate the looper with respect to the needle according to whether it is desired to produce chain- or drop-stitches. To conveniently and accurately effect this adjustment, the spiral-gear 17 is formed at one end with an internally recessed head 19 receiving a coil-spring 20, which acts in a direction to yieldingly seat upon a pin 21, provided upon the shaft 18, the selected one of two notches, as 22, at the opposite ends of a slot 23, formed in the head 19, which slot is of sufficient width to permit passage of the pin 21. It will be apparent that by shifting the spiral gear 17 upon the shaft 18 in a direction to compress the spring 20, said gear 17 may be rotated upon the shaft 18 so that the selected one of the two notches 22 may be caused to engage the pin 21. Consequently the spiral-gear 17 may be locked to the shaft 18 in either of the positions defined by the notches 22, which notches are properly spaced to obtain the desired looper positions for producing either drop or chain-stitches.

The looper-actuating shaft 18 is journaled for rotary and endwise reciprocatory movements in bearings provided in brackets 24, 25 depending from the cloth-plate 1, the shaft 18 adjacent its rearward end being splined to the hub 26 of a bevel-gear 27 journaled for rotation in a bearing-aperture in the bracket 25. The hub 26 is held against endwise movement with respect to said bracket 25 by means of a collar 28. At its rearward end, the shaft 18 is suitably connected with a depending arm 29 of a bell-crank lever fulcrumed within the bracket-arm standard 2 upon a pivot-pin 30

disposed transversely of the length of the shaft 18. The other arm 31 of the bell-crank lever is suitably connected with the lower end of a pitman 32 provided at its upper end with a strap 33 embracing an eccentric 34 having a hub 35 fixed upon the shaft 9. It will therefore be evident that when the shaft 9 is rotated, the shaft 18, through the described connections with the eccentric 34, derives endwise reciprocatory movements whereby the looper 15 is oscillated about its vertical axis to position the needle-thread for engagement by the hook of the needle in the usual manner.

The hub 35 of the eccentric 34 is embraced by the correspondingly recessed flange 36 of a cam-sleeve 37, provided with a cam-groove 38 and slidably mounted upon the shaft 9. Projecting from the flange 36 is a coupling-pin 39, slidable endwise through an aperture provided in the eccentric 34 and adapted to enter an aperture in a coupling-collar 40 fixed upon the shaft 6. Bearing against the cam-sleeve 37 is a coil-spring 41, surrounding the shaft 9 and interposed between said cam-sleeve and a collar 42 fixed upon the shaft 9. When permitted, the spring 41 acts to cause coupling engagement of the pin 39 with the collar 40, whereby the shaft 9 is joined to the shaft 6 for rotation therewith.

Means are provided for normally holding the coupling-pin 39 disengaged from the collar 40, for which purpose the cam-groove 38 is entered by a roller carried by the free end of a vibratory-arm 43, pivotally supported upon the machine frame within the standard 2. Adjustably connected to the arm 43, by means of an eccentric stud 44, is one end of a connecting-lever 45, disposed within the bracket-arm 3 and formed intermediate its ends with an elongated slot 46 to provide guide-walls slidable upon a fulcrum-block 47, pivotally secured by means of a screw 48 to the machine frame. The other end of the lever 45 is shouldered to provide a depending latch-hook 49 adapted to be engaged by an upwardly directed latch-hook 50 formed on one end of a lever 51, pivotally supported within the bracket-arm 3 upon a pivot-screw 52. The latch-hook end of the lever 51 is yieldingly urged upwardly to engage the latch-hook 49 by means of a spring 53 interposed between said lever and the bottom of the bracket-arm. In Fig. 1 of the drawings, the lever 51 is shown as latched to the lever 45 whereby the vibratory-arm 43 is held against movement to the right. The arm 43 being held against movement to the right, it will be evident that upon further rotation of the shaft 9, the cam-sleeve 37 will be shifted to the left upon the shaft 9, against the action of the spring 41, which has the effect of withdrawing the coupling-pin 39 from the aperture in the collar 40. The shaft 18

9 thus disconnected from its driving power would eventually come to rest.

However, means are provided for predetermining the stopping position of the shaft 9. By referring to Fig. 3 of the drawings, it will be observed that the periphery of the cam-sleeve flange 36 is formed with a V-shaped stop-notch 54, which in the position occupied by the sleeve when uncoupled from its driver, is adapted to be entered by the wedge-shaped end of a plunger-head 55. The plunger-head 55 is slidingly supported for endwise movement within the bore of a tubular bracket 56 suitably secured in an aperture in the rear side of the standard 2, said plunger-head having a reduced extension 57, surrounded by a coil-spring 58 interposed between the plunger-head and an adjustable bushing 59 threaded into the bracket 56. The inward movement of the plunger under the action of the spring 58 is adjustably limited by a nut 60 threaded upon the outer end of the plunger-extension 57 and engaging the head of the bushing 59. The adjustment provided by the eccentric stud 44 affords means for slightly altering the timing to insure entrance of the flange-notch 54 by the plunger 55.

In order to rotate the cylinder 10 under manual control, there is secured upon said cylinder a bevel-gear 61 in mesh with a similar gear 62 upon the forward end of a feed-direction controlling shaft 63 journaled for rotation in bearings provided in the bracket-arm 3. Intermediate its ends, there is secured upon the shaft 63 a bevel-gear 64 meshing with a like gear 65 secured upon the upper end of a tubular shaft 66 projecting within the bracket-arm 3. The tubular shaft 66 is journaled for rotation about a vertical axis in a bearing provided by a boss 67 depending from the bracket-arm 3. Secured upon the end of the shaft 66 projecting below the boss 67, is a crank-arm 68 carrying a crank-handle 69, which as usual in machines of this type is capable of slight movement in a direction at right angles and with respect to the crank-arm 68. The crank-handle 69 has a peripheral groove 70 operatively engaging one arm of a lever 71 fulcrumed intermediate its ends upon the crank-arm 68. Engaged by the flattened end 73 of the other arm of the lever 71 is a pin 74 slidingly disposed within the tubular-shaft 66, the upper end of the pin 74 being positioned to engage the depending end 75 of the lever 51. It is apparent that a downward movement of the crank-handle 69 effected manually, causes a rocking movement of the lever 51, against the action of the spring 53, to release the connecting lever 45 and thereby permit the spring 41 to effect in due course the coupling of the shafts 6 and 9.

Heretofore in machines of this type, when the nature of the work was such as to permit

of continuous stitching, certain of the parts of the stop-motion controlling mechanism were removed from the machine so as to obviate the requirement for the operator to maintain the shafts 6 and 9 coupled by means of the crank-handle 69. To in a simple manner provide for contingencies of this character, a screw 72 is threaded into the hub of the crank-arm 68 in a position such that it may be caused to engage and secure the pin 74. Therefore, when the pin 74 is elevated to disconnect the stop-motion controlling levers 45, 51, it may readily be secured in its raised position by means of the screw 72.

The rearward end of the feed-direction controlling shaft 63 is geared to the upper end of a vertical shaft 76, journaled for rotation in bearings provided in the standard 2 and carrying at its lower end a bevel-gear 77 meshing with the bevel-gear 27, which as before described is splined to the looper-actuating shaft 18. It will therefore be understood that upon manual actuation of the crankhandle 69 to rotate the same about the axis of the shaft 66, the described connections with said shaft 66 will effect rotation of the cylinder 10 and of the needle carrying bar 11 splined thereto, as well as rotation of the looper in correspondence with the resultant positions of the needle.

The feeding mechanism of this machine, with the exception of the present improved feed-length adjusting mechanism, is substantially as disclosed in greater detail in my prior Patent No. 1,325,033 before referred to. In general, the feeding mechanism includes a feeding-foot or -ring 78 which is detachably secured upon the lower end of a feed-bar 79 supported at its upper end for universal movement about transverse pivotal axes. For this purpose, the upper end of the feed-bar 79 is bifurcated to provide the spaced arms 80, disposed at opposite sides of the cylinder 10 and which are pivotally secured by screws, as 81, upon the arms of a bifurcated fulcrum-pin 82, the pivotal axis afforded by the screws 81 preferably intersecting the axis of rotation of the cylinder 10. The pivot-pin 82 is journaled in a bearing provided by a bracket 83 to permit of swinging movements of the feed-bar 79 upon an axis transverse to the pivotal axis afforded by the screws 81, said bracket 83 being confined to vertical reciprocatory movements upon the supporting-frame 5. The bracket 83 projects laterally from a vertically reciprocating sleeve 84, which is raised by the usual operative connections with a feed-lift-cam 85 upon the forward end of the shaft 9 and is lowered by a spring (not shown) housed within the sleeve 84. It is preferred to employ an eccentric fulcrum-stud 86 for the feed-lift lever 87 which is actuated by the cam 85, whereby the lift of the feeding-foot may be slightly adjusted.

The work advancing movements of the feeding-foot 78 are derived from a cam 88 upon the shaft 9, which cam actuates a lever 89 adapted to engage a lug 90, projecting from a vertically sliding sleeve 91 and extending through a slot in the frame 5. The lever 89 operates to lower the sleeve 91 against the action of a spring 92 housed within the sleeve, said spring being interposed between an adjustable bushing 93 threaded into the upper end of the sleeve and the upper end of a stripper-foot bar 94 constituting a guiding support for the lower end of the sleeve 91. Projecting laterally from the sleeve 91 is a forked arm 95 embracing and sustaining a grooved collar 96 having a sliding fit upon the cylinder 10. In the present instance, the collar 96 is formed integral with a fulcrum-block 97 provided with a transverse aperture 98 for the reception of a pin 99 suitably secured to said block by a screw 100. The fulcrum-block 97 is provided in its opposite flat sides with arcuate guideways 101 (only one of which is shown) for guide-ribs 102 (only one of which is shown) formed on the inner surfaces of the spaced arms 103 of a feed-finger actuating cam-member 104. The spaced arms 103 are further provided with arcuate slots 105 which are entered by the pin 99 upon the ends of which are threaded nuts 106 serving to secure the cam-member 104 in any position into which it may be adjusted about an axis constituting the center of curvature of the guide-ribs 102.

The cam-member 104 is provided with a flat-faced cam-groove 107 adapted to be engaged by the end of a feed-lever 108, the point of engagement of said lever 108 with the cam-groove 107 at the beginning of a work-feeding movement of the feeding-foot constituting approximately the center of arcuate adjustment of the cam-member. The feed-lever 108 is fulcrumed between spaced ears formed upon a guide-block 109, suitably secured upon the cylinder 10 and adapted to guide a feed-collar 110 which is actuated in one direction by the feed-finger 108 and in the return direction by springs, as 111. The feed-collar 110 is embraced by a ring 112 projecting from the feed-bar 79.

In the crank embroidering machines of the present type, it has been a common practice to obtain adjustments for varying the stitch-lengths by providing variable lost-motion actuating connections for the feed-cam upon the cylinder 10. As a result, the feed-finger engaged the feed-cam at different points of the length of the feed-cam groove at the beginning of the feeding movement for each selected stitch-length. As consequently the feeding-foot did not occupy a position concentric with the needle at the beginning of its feeding movement for the different extents of adjustment of the stitch-lengths, it is evident that changes in the direction of feed

under manual control effected different lengths of successive stitches. While this discrepancy was present, it was heretofore discounted in the prior smaller machines because of the relatively short stitch-lengths. To avoid this discrepancy in the present large machine, which makes relatively long stitches, the feed adjustment has been changed as described to insure a constant position of the feeding-foot with respect to the needle at the beginning of each feeding movement, regardless of the length of the stitches selected.

Alternating with the feeding-foot 78 in its work-engaging movements is a conical stripper-foot 113, which embraces the needle 13 and is formed with a reduced shank 114 secured within a sleeve 115 journaled for end-wise reciprocatory movements in a bearing-boss 116 depending from the frame 5. Projecting laterally from the upper end of the sleeve 115 is an arm 117, in the present instance integral with the bar 94 to the upper end of which bar is secured a screw-pin 118 projecting into a slot (not shown) formed in the frame 5. In order to lift the bar 94 against the action of the spring 92, the screw-pin 118 is positioned to be engaged by a lever 119 actuated by the feed-lift cam 85. The sleeve 115 is tubular to receive the lower end of the cylinder 10, thereby constituting the direct journal-bearing of the lower end of said cylinder 10.

As is well known in machines of this class, the feeding-foot 78 comprises a ring of pointed teeth 120 of which all the points terminate in substantially a common horizontal plane. To insure greater uniformity in the feed of the work throughout the length of the work-feeding movement of said foot 78 and regardless of the direction of feed, the throat-plate 121 of the machine is formed with an upper, dished surface 122, having as a center of curvature the point of intersection of the transverse pivotal axes of the feed-bar 79, when the feeding-foot is in engagement with the throat-plate. By means of this construction, the teeth of the feeding-foot all engage the work at the beginning of the feeding movement, regardless of the direction of feed, and maintain their engagement with the work throughout the feed stroke, thereby obviating any stretching or fulling action particularly when acting upon thin or flimsy materials.

The present machine is operated in the regular fashion of machines of this type, the crank-handle 69 for controlling the feed-direction and the stop-motion being now positioned so that the work upon the cloth-plate does not interfere with the convenient manipulation of said crank-handle. By securing the pin 74 by means of the screw 72, the machine may be maintained in operation without constant manipulation of the crank-

handle 69 for this purpose. It will be observed that the location of the stop-motion actuating connections within the bracket-arm 3, instead of in the standard 2 as heretofore, affords sufficient clearance within said standard for the fulcrum of the bell-crank lever 29, 31, whereby the free end of the arm 29 of said lever describes a path of movement above the lowest portion of the machine-bed, instead of projecting below the bed as in prior machines. The described adjustment for changing the stitch-length is such as to maintain any selected stitch-length uniform when feeding in different directions, while the dished throat-plate obviates stretching and fulling of flimsy materials.

Novel features of construction of the stop-motion device disclosed but not claimed herein form the subject of my divisional patent application Serial No. 309,143, filed September 29, 1928.

Having thus set forth the nature of the invention, what I claim herein is:—

1. In a universal-feed sewing machine, a cloth-plate, a bracket-arm overhanging the cloth-plate, stitch-forming mechanism, work-feeding mechanism including a feeding-foot adapted to receive work-advancing movements in different directions, actuating means for said stitch-forming and work-feeding mechanism, a stop-motion device embodied in the machine for determining the operation of said stitch-forming and work-feeding mechanisms, and a manually operable member upon said bracket-arm for controlling the direction of feed of the work and the operation of said stop-motion device.

2. In a universal-feed embroidering machine, stitch-forming mechanism including a reciprocatory needle, a feeding-foot having work-feeding movements in different directions substantially transverse to the path of reciprocation of the needle, a feeding-foot carrying bar, a universal pivotal support for said feed-bar, and a dished work-support within the range of movement of the feeding-foot, said dished work-support having its center of curvature substantially in the pivotal axis of the feed-bar in the work-support engaging position of said foot.

3. In a sewing machine, a reciprocatory needle, a feeding-foot, a feeding-foot carrying bar, a pivotal support for said bar, and a curved work-support opposed to said feeding-foot, the center of curvature of said work-support coinciding substantially with the pivotal axis of said feed-bar in the work-support engaging position of said feeding-foot.

4. In a universal-feed sewing machine, in combination, stitch-forming mechanism including a vertically reciprocatory needle-bar, a feeding-foot adapted to receive work-advancing movements in different directions, a reciprocatory cam-member, means for re-

ciprocating said cam-member, operative connections between said cam-member and the feeding-foot to impart the work-advancing movements to said feeding-foot, and means permitting adjustment of said cam-member to vary the extent of the work-advancing movements of the feeding-foot from a constant initial position of said foot.

5. In a sewing machine, in combination, stitch-forming mechanism, a feeding foot, an actuating shaft, a cam-member deriving right line reciprocatory movements from said shaft, means for imparting work-advancing movements to the feeding-foot from said cam-member, and means for tilting said cam-member with respect to its path of reciprocation to thereby vary the extent of work-advancing movements of the feeding-foot.

6. In a universal-feed sewing machine, in combination, stitch-forming mechanism including a vertically reciprocatory needle-bar, a feeding-foot, a reciprocatory cam-member, a feeding-foot actuating lever operatively engaged by said cam-member, and means permitting adjustment of said cam-member about an axis which is approximately coincident with the point of engagement of said feed-lever with the cam-member at the beginning of the work-advancing movement of said feeding-foot.

In testimony whereof, I have signed my name to this specification.

WALTER MYERS.
